UNITED STATES PATENT OFFICE.

JAMES F. BOBBITT, OF GREENWOOD, MISSISSIPPI.

TILE ROOFING.

Application filed March 19, 1924. Serial No. 698,257.

To all whom it may concern:

Be it known that I, JAMES F. BOBBITT, a citizen of the United States, residing at Greenwood, in the county of Leflore and

5 State of Mississippi, have invented certain new and useful Improvements in Tile Roofing; and I do hereby declare the following to be a full, clear, and exact description of the invention, such as will enable others 10 skilled in the art to which it appertains to make and use the same.

This invention relates to improvements in tile roofing wherein the tiles are constructed from flexible material and has for 15 its object to provide improved securing means for holding the tile in place.

The various features of the invention will appear from the detailed description taken 20 in connection with the accompanying sheet of drawings forming part of this specification and wherein—

Fig. 1 is a vertical cross-section taken through a section of roof showing the application of my invention.

25 Fig. 2 is a plan view of Fig. 1;

Fig. 3 is a bottom perspective view of one of the tile members showing a stiffening member arranged therein; and

30 Fig. 4. is a perspective view showing the improved securing means for holding the tile in place.

In the drawings, numeral 1 indicates the supporting boards usually laid over the rafters of the roof. Arranged up and down on 35 the boards 1 is a plurality of parallel spaced bars 2. Between the bars 2 is laid a section of roofing 3 the sides thereof being secured to the bars 2 in any suitable manner. Said sections 3 are preferably of a length to correspond to a tile section though it may be 40 continued as one piece if found desirable; however, by making the sections 3 in short lengths the roof is given a more complete appearance as a regular tile roof, as will be 45 readily understood.

The bars 2 and the ends of the roof section 3 are covered over by a curved member 4 and said member is preferably braced by means of an arched member 5 arranged 50 therein and secured thereto in any suitable manner.

After one course of curved members 4 has been laid, there is positioned over the 55 upper ends of said members a curved saddle member generally indicated by numeral 6, the saddle being secured to the underlying

bar 2 by means of a nail 7 which is driven through the curved member 4 into said bar. This nail secures the curved member 4 in position with respect to said bar.

60 The saddle member 6 is provided with terminal hooks 8 and a laterally extending hook 9. When the next course of curved tile members 4 is laid the lower ends of the tile members 4 will be inserted into the hook member 9 and thus be properly positioned as to weather as will be readily understood. The longitudinal side edges of the curved tile 4 are seated in the hooks 8 and are consequently held against lateral 65 spreading. This manner of laying the tile members is continued until the roof has been completed when the ridge thereof can be capped in any suitable manner.

70 In the drawings I have shown the saddle 75 6 as being made up from a single piece of wire bent into bowed shape and a lateral extension provided with an opening 7' through which a nail may be driven, but it is to be understood that the saddle can be 80 made in various ways without departing from the spirit of the invention, the form shown being merely an example of a simple form of saddle. The main features of the saddle are that it has terminal hooks at its 85 bowed ends and a lateral hook into which the butt end of the tile may be received.

90 My invention makes possible the laying of tile roofing made of flexible material in such a manner that the roofing will be held firmly in place, more particularly the curved or cap members 4 which extend over the bars 2 and the upstanding ends of the intermediate roofing members 3. The saddle securely holds the bottom ends of the cap 95 members in place, and the hook 9 additionally serves to hold the butt end of the said cap member from separating from the adjacent member.

100 What I claim is:

1. As a new article of manufacture, a curved member having upturned hooks at its terminals and provided intermediate its terminals with a laterally directed upturned hook.

105 2. As a new article of manufacture, a curved member having upturned hooks at its terminals, and having a laterally extending member intermediate its ends provided at its terminal with an inturned hook.

110 3. In a roof covering, the combination of

flexible curved tile members arranged in overlapped relation, means for securing the upper overlapping member in fixed position with respect to the underlying member comprising a curved saddle disposed between said members and having hooked terminals into which the side edges of the upper member is received, and means for securing the saddle in fixed position with respect to the underlying tile member.

4. The combination specified in claim 3, and a lateral extension secured to said saddle intermediate the ends thereof and having an inturned hook at its terminal into which the end edge of the overlying tile is received and held against displacement.

5. In combination, a roof support, a plurality of bars secured in up and down par-

allel relation thereon, a flat tile section disposed between said bars, a curved tile disposed over a said bar and the side edges of the flat member disposed between said bars, a second curved tile disposed over the first like member in overlapped relation, means securing the overlapped end of the tile member comprising a saddle seated over the upper end of the underlying tile member and having hooked terminals adjacent the bottom side edges of the same into which terminals the side edges of the overlying tile are received, a lateral extension from said saddle having a hooked end into which the butt end of said overlapping tile is received, and means for securing said saddle and extension in place on said bar.

In testimony whereof I affix my signature.

JAMES F. BOBBITT.
